Primary Examiner — Rhea Shields

(57) **CLAIM**

The ornamental design for a nasal spray device, as shown and described.

DESCRIPTION

1. Nasal spray device

1.1: Perspective

1.2: Front

1.3: Back

1.4: Right

1.5: Left

1.6: Top

1.7: Bottom

The broken lines shown in the drawings illustrate portions of the article and form no part of the claimed design.
